US00D585997S

(12) **United States Design Patent**
Adam et al.

(10) **Patent No.:** US D585,997 S
(45) **Date of Patent:** ** Feb. 3, 2009

(54) **LIGHT-BASED DERMAL ENHANCING APPARATUS**

(75) Inventors: **Horst R. Adam**, San Mateo, CA (US); **Victor C. Esch**, Albuquerque, NM (US); **Marc P. Maisel**, Los Altos, CA (US); **Joseph Robert Rimsa**, Palo Alto, CA (US)

(73) Assignee: **Light Dimensions, Inc.**, Palo Alto, CA (US)

(**) Term: **14 Years**

(21) Appl. No.: **29/275,315**

(22) Filed: **Dec. 20, 2006**

(57) **CLAIM**

The ornamental design for a light-based dermal enhancing apparatus, as shown and described.

DESCRIPTION

FIG. 1 is a perspective view of a light-based dermal enhancing apparatus, showing our new design;

FIG. 2 is a left side view of the light-based dermal enhancing apparatus of FIG. 1;

FIG. 3 is a right side view of the light-based dermal enhancing apparatus of FIG. 1;

FIG. 4 is a top view of the light-based dermal enhancing apparatus of FIG. 1;

FIG. 5 is a bottom view of the light-based dermal enhancing apparatus of FIG. 1;

FIG. 6 is a front view of the light-based dermal enhancing apparatus of FIG. 1; and,

FIG. 7 is a rear view of the light-based dermal enhancing apparatus of FIG. 1.
